UNITED STATES PATENT OFFICE.

GEORGE K. SMITH, OF CAMDEN, NEW JERSEY, ASSIGNOR OF ONE-THIRD TO HAROLD E. McCRARY AND ONE-THIRD TO ALBERT E. JESSER, BOTH OF PHILADELPHIA, PENNSYLVANIA.

WREATH FORM.

Application filed August 25, 1922. Serial No. 584,374.

To all whom it may concern:

Be it known that I, GEORGE K. SMITH, a citizen of the United States, residing at Camden, in the county of Camden and 5 State of New Jersey, have invented certain new and useful Improvements in Wreath Forms, of which the following is a specification.

This invention relates to wreath forms 10 and more particularly to such a form intended for use by florists and others and adapted to be covered with suitable decorative material.

An important object of the invention is 15 to provide a device of the above mentioned character formed of a pair of sections adapted to be held in place by the material with which it is covered.

A further object of the invention is to 20 provide such a form having means for securing the ends of the decorative material with which it is covered.

Other objects and advantages of the invention will be apparent from the course of 25 the following description.

In the drawings, I have shown one embodiment of the invention. In this showing,

Figure 1 is a face view of the device, a 30 few turns of the decorative material being shown applied thereto,

Figure 2 is a fragmentary detail perspective of a portion of the complementary members, and,

Figure 3 is a section taken on line 3—3 of Figure 1.

In the drawings, the reference numeral 5 designates as a whole the wreath form comprising a pair of complementary members 6 and 7. The complementary members are substantially semi-circular in cross-section as clearly shown in Figures 2 and 3.

The complementary members 6 and 7 are adapted to be placed edge to edge as shown 45 in Figure 3, to form substantially a hollow shell. The edges of the complementary members are provided at spaced intervals with lips 8, the spaces between the lips being approximately equal to the lengths of 50 the lips whereby the lips of one member are adapted to be received between the lips of the opposite member. As shown in Figure 3, each of the lips 8 is adapted to contact with the outer face of the opposite complementary member whereby lateral displace-

ment of the complementary members is prevented.

Each of the complementary members is provided substantially centrally thereof with a continuous groove 9 extending 60 around the ring for a purpose to be described. The members 6 and 7 are provided within the groove 9 with openings 10 stamped through the metal to provide inwardly extending points 11. Between the 65 grooves 9 and the edges of the complementary members the metal is provided with a plurality of smaller openings 12, similar to the openings 10, the metal being stamped to provide gripping points 13 extending inwardly of the opening.

It will be seen that the complementary members 6 and 7 are identical so that in the manufacture of the device it is necessary to employ but a single set of die forms for 75 the production of these members. The complementary members 6 and 7 are preferably formed of sheet metal and are stamped in the shape shown in Figure 2, the die operation providing the lips 8 and grooves 80 9, the body portion of the members being stamped into semi-cylindrical shape as shown. After the members have been completed to the stage shown in Figure 2 they are again subjected to a stamping operation 85 whereby the openings 10 and 12 are formed.

The operation of the device is as follows:

The complementary members 6 and 7 are placed in edge to edge relation with the lips of each member registering with the spaces between the lips of the other member, and the two members pressed together whereby the lips 8 of each member will frictionally engage the outer face of the 95 other member. Suitable decorative material, preferably in string form as shown at 14, is then wrapped about the form. The free end of the material is preferably laid a short distance along and within one of the 100 grooves 9 and the material then wrapped about the form, successive turns being adapted to hold the end of the material in place to prevent it from becoming loose. The material is wrapped completely about 105 the ring and the end of the material inserted within the groove 9 beneath the last turns of the material about the form. Thus it will be seen that the free ends of the decorative material employed are firmly 110

held in position about the form. Where a single strand of the decorative material is not sufficient to cover the entire form, the free end of one strand may be joined with 5 the beginning of a succeeding strand and the ends inserted within one of the openings 10, the points 11 engaging the material to hold it firmly in place. It is often desired to cover a wreath with artificial 10 flowers. In the present invention such flowers may be applied to the device by inserting the stems between the turns of the decorative material and forcing them through the openings 12, the flowers being 15 securely held in position by the gripping action of the points 13. It will be obvious that when it is desired to employ natural flowers or leaves upon the wreath, the form may be filled with moist moss before assembling and when the leaves or flowers are applied, their stems will be embedded within 20 the moss to absorb moisture therefrom.

It is the present practice to provide forms of papier mâché or the like, covered with 25 artificial decorative material. While the decorative material may be kept indefinitely, as from one selling season to another, and freshened by steaming, the papier mâché forms upon which the material is wound 30 will not withstand the steaming process but will soften and collapse. When the present wreath form is employed, however, the finished wreaths may be stored between selling seasons and then easily freshened by steaming, the steaming operation having no destructive effect upon the sheet metal of 35 which the form is made.

It is to be understood that the form of my 40 invention herewith shown and described is to be taken as a preferred example of the same and that various changes in the shape, size, and arrangement of parts may be resorted to without departing from the spirit of the invention or the scope of the subjoined claims.

Having described my invention, I claim:

1. A wreath form comprising a substantially ring shaped shell provided in one face with a continuous groove, said shell being 50 further provided with an opening formed at the bottom of said groove by stamping the

material of the shell inwardly to form edges adapted to grip the end of the material with which the shell is wrapped.

2. A substantially ring shaped wreath 55 form comprising a pair of complementary sheet metal members, the contiguous edges of said members being provided with spaced lips, the lips of each member being received between the lips of the other member to prevent lateral displacement of said members, said members being adapted to be held together by the decorative material with which they are wrapped.

3. A substantially ring shaped wreath form 65 comprising a pair of complementary sheet metal members, the contiguous edges of said members being provided with spaced lips the lips of each member being received between the lips of the other member to prevent lateral displacement of said members, 70 said members being adapted to be held together by the decorative material with which they are wrapped, each of said members being provided with a continuous groove. 75

4. A substantially ring shaped wreath form comprising a pair of complementary members, the contiguous edges of said members being provided with spaced lips, the lips of each member being received between the lips of the other member to prevent lateral displacement of said members, 80 said members being formed of sheet material whereby to form an internal space when assembled, and being adapted to be held together by the 85 material with which they are wrapped, each of said members being provided with a circular groove having an inwardly stamped opening therein, the outer portions of said members being provided with a plurality of 90 relatively small inwardly stamped openings.

5. A device of the character described comprising a body adapted to be covered with rope like decorative material, said body being provided with a groove substantially 95 equal in depth to the thickness of the decorative material and adapted to receive the ends thereof whereby they may be frictionally held in place by the material arranged across said groove. 100

In testimony whereof I affix my signature.
GEORGE K. SMITH.
